CLAIM

The ornamental design for a confection, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top, front, left side perspective view of a first embodiment of a confection showing our new design;

FIG. 2 is a top plan view thereof;

FIG. 3 is a top, front, left side perspective view of a second embodiment of a confection;

FIG. 4 is a top, front, left side perspective view of a third embodiment of a confection; and,

FIG. 5 is a top, front, left side perspective view of a fourth embodiment of a confection.

The dash-dot lines in FIGS. 1-5 and the areas within the dash-dot lines shown in phantom show portions of the confection that form no part of the claimed design.
